UNITED STATES PATENT OFFICE.

WILLIAM M. HORTON, OF CLEVELAND, OHIO.

DESIGN FOR A FLAG CARRIER AND ILLUMINATING DEVICE FOR MOTOR-VEHICLES.

51,177.

Specification for Design.

Patented Aug. 21, 1917.

Application filed May 16, 1917. Serial No. 169,136. Term of patent 7 years.

To all whom it may concern:

Be it known that I, WILLIAM M. HORTON, a citizen of the United States, residing at Cleveland, county of Cuyahoga, and State of Ohio, have invented a new, original, and ornamental Design for a Flag Carrier and Illuminating Device for Motor-Vehicles, of which the following is a specification, reference being had to the accompanying drawing, forming part thereof.

In the accompanying drawing,

Figure 1 is a side view; and Fig. 2 is a top plan view, showing my new design.

I claim as my invention:

The ornamental design for a flag carrier and illuminating device for motor vehicles, substantially as shown.

Signed at Cleveland, county of Cuyahoga, and State of Ohio, this 14th day of May, 1917.

WILLIAM M. HORTON.
